(57) **CLAIM**

The ornamental design for an electrical device, as shown and described.

DESCRIPTION

A portion of the disclosure of this patent document contains material which is subject to copyright protection. The copyright owner has no objection to the facsimile reproduction by anyone of the patent disclosure, as it appears in the Patent and Trademark Office patent files or record, but otherwise reserves all copyright rights whatsoever.

FIG. 1 is a front elevation view of an electrical device showing our new design in a typical usage configuration;

FIG. 2 is a back elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front perspective view thereof;

FIG. 8 is a front elevation view of an electrical device showing our new design in an alternate typical usage configuration;

FIG. 9 is a back elevation view thereof;

FIG. 10 is a left side elevation view thereof;

FIG. 11 is a right side elevation view thereof;

FIG. 12 is a top plan view thereof;

FIG. 13 is a bottom plan view thereof; and,

FIG. 14 is a front perspective view thereof.

The claimed design can be used, for example, as a plug-in timer.

The broken lines show unclaimed subject matter only and form no part of the claimed design.
